GEORG MARX, JR., OF NUEREMBERG, GERMANY, ASSIGNOR TO THE FIRM OF VEREINIGTE MASCHINENFABRIK AUGSBURG UND MASCHINENBAUGESELLSCHAFT NÜRNBERG A.-G., OF NUEREMBERG, GERMANY.

SPEED-REGULATOR FOR EXPLOSIVE-ENGINES.

SPECIFICATION forming part of Letters Patent No. 777,295, dated December 13, 1904.

Application filed March 3, 1903. Serial No. 145,968. (No model.)

To all whom it may concern:

Be it known that I, GEORG MARX, Jr., engineer, a subject of the Emperor of Germany, residing in Nuremberg, in the Empire of Germany, (whose full postal address is 35 Martin Richterstrasse, Nuremberg, aforesaid,) have invented certain new and useful Improvements in Speed-Regulators for Explosive-Engines, of which the following is a specification.

10 This invention has for its object a releasing distributing-gear for the gas-valve of gas-engines working with qualitative regulation.

The object of the invention is to operate the gas-valve by means of a simple eccentric gear, 15 so that the opening of the valve alters with the load, while the cut-off of the valve always takes place at a certain position of the engine-crank—that is to say, is unalterable. The time for the opening of the valve is so selected 20 that at the lowest position of the governor (corresponding to the biggest loading on the engine) it is somewhat in front of the commencement of the suction-stroke, while it alters with the stroke of the governor, and 25 when the governor is in its highest position coincides with the cut-off at the end of the suction-stroke, so that in this position the gas-valve is not opened.

Now the present invention endeavors to 30 solve the problem of meeting all the requirements hereinbefore enumerated by the combination of a roller-lever system regulated by the action of the governor, and thereby causing the alteration of the opening-point, 35 and a releasing mechanism always snapping off at the same point of time, and thereby maintaining a constant cut-off.

The invention is shown in the accompanying drawings in vertical section in Figures 1 and 2, while Fig. 3 represents the new valve-governor in its application to an explosive-power engine.

The passive roller-track is formed by a lever *w*, one end of which is pivotally mounted 40 in a valve-yoke *y*, and its other end, which has a steeply-inclined track *s*, rests on the roller of a lever *u*, regulated by the action of the governor. The rear end of the active roller-lever

50 *b* is pivotally connected with a valve-spindle *v* in such a way that its axis of rotation when the valve is closed coincides with the axis of rotation of the roller-track *w*. As thus the point of rotation of the passive roller-track is on the same axis as the point at which when the valve is closed the active roller-lever 55 engages the valve-spindle, both levers *b* and *w* always encounter one another in the same position, and this position is independent of the actual condition of the governor. Consequently these levers always meet without 60 shock if the system has been correctly worked out from one position. The lever *u*, carrying a roller *r*, is connected with a governor-spindle *t*, so that the roller-track *w*, which rests by means of its steeply-inclined track *s* 65 on the said roller, assumes a higher or lower position, according to the condition of the governor. The disconnecting mechanism is formed of a free-hanging pawl *k*, mounted at the point *a*, which pawl by means of an insertion-piece *m* slides on a similar insertion-piece *m* in the lever *b*. The touching-surfaces of the pieces *m* are curved on a circle the center of which is formed by the pivot *a*. The pawl *k* is provided with a downwardly-extending 70 projection which carries a steeply-inclined track *o*. An eccentric-rod *e* is also pivoted on a link *l* at the point *a*, which at the other side is revolvably connected at the point *e* with the valve-lever *b*. The rod *e* is 75 moved up and down in the ordinary manner by means of an eccentric keyed firmly on the way-shaft 2. This movement causes the steeply-inclined track *o* to travel on its roller *q*, and thereby releases the lever *b* from the 80 pawl *k*. The releasing-roller *q* in the form of construction shown in the drawings is mounted on a projection of the air-buffer casting *z*, the air-buffer *n* of which is linked to the front end of the valve-lever *b* and rests 85 on a lifting-spring *i*, bearing against the bottom of the casing *z*.

The distribution is in the accompanying drawings supposed to be with a closed valve and at the moment of the commencement of 90 the contact of both roller-levers, Fig. 1 show-

ing the lowest and Fig. 2 the highest position of the governor. The distribution shown in Fig. 1 at the lowest position of the governor and with the valve closed is effected in the following manner: In the downward movement of the eccentric-rod the parts *k l b* are moved downward, constantly pressing the pawl *k* downward also, whereby contact is produced between the parts *b* and *w* earlier or later, according to the position of the governor, and thus the lift of the valve commences. The pawl *k*, after reaching the disengaging-position which remains constant for all positions of the governor, releases the lever *b*, whereby the valve closes under the action of its own weight and a valve-closing spring *f*, while at the same time the part *b* travels along the part *w*. The complete return of the lever *b* to its initial position is effected by means of the lift-spring *i* and the air-buffer *n*. After the release of the pawl the eccentric-rod *e* and pawl *k* and link *l* continue the movement; but shortly before the highest position is reached the pawl *k* engages, so that the steeply-inclined track *o* again encounters the roller *q*, and in order to deaden the sound of the roller dropping on the track the respective part of *o* is made resilient, for instance, by the placing thereon of a strip of leather *x*. The movement can then recommence.

The sliding lever *w* occupies various positions, according to the position of the governor, while the outer end *m* of the active sliding lever *b* is constantly moved in the same manner by means of pawl *k*. Consequently the contact between the two sliding levers *b* and *w*, and therefore also the beginning of the valve motion, occur at varying points of time. Moreover, the stroke of the valve depends at every point upon the respective position of the governor—that is to say, not only the point of time when the valve opens but also the stroke of the valve are influenced by the governor.

The arrangement of valve distribution here-

inbefore described necessitates when the valve is closed the arrangement of the passive and active levers on a uniform axis, so that a lift is obtained free from shock, if it be ascertained for one position. As the air-buffer, in consequence of the time of snapping in of the pawl being the same at all charges, describes the same course, a constant position of the air-suction valve may be maintained and a quiet and uniform closing of the valve attained.

I declare that what I claim is—

1. In combination, a valve, a lever *b* connected thereto, a movable fulcrum for the said lever comprising a lever *w*, a governor for controlling the position of the said lever *w*, mechanism for operating the lever *b* arranged to be disengaged therefrom, and means for throwing the said mechanism out of engagement with the said lever *b* at a certain point of the stroke, substantially as described.

2. In combination with a valve, a lever *b* pivotally connected thereto, a fulcrum for the said lever comprising a lever *w* with a pivot-support therefor, means operating the lever *b* and means for controlling the position of the lever *w*, the pivotal points of the levers *b* and *w* being axially in alinement when the valve is closed.

3. In combination a valve, a lever pivotally connected therewith, pawl *k* for engaging the lever, said pawl being suspended from a pin *a*, means for connecting the said pin with the said lever, means for reciprocating the pawl to engage the lever and means for throwing the said pawl out of engagement with the said lever, said engaging and said disengaging action occurring at the same points in the stroke of the pawl *k*, substantially as described.

In witness whereof I have hereunto set my hand in presence of two witnesses.

GEORG MARX, JR.
